UNITED STATES PATENT OFFICE.

WILLIAM B. CHARLTON, OF PHILADELPHIA, PENNSYLVANIA.

MEAT, HAMMOCK, OR OTHER HOOK.

SPECIFICATION forming part of Letters Patent No. 423,730, dated March 18, 1890.

Application filed April 11, 1889. Serial No. 306,870. (No model.)

To all whom it may concern:

Be it known that I, WILLIAM B. CHARLTON, a citizen of the United States, residing in the city and county of Philadelphia, State of Pennsylvania, have invented a new and useful Improvement in Meat, Hammock, or other Hooks, which improvement is fully set forth in the following specification and accompanying drawings.

10 My invention consists of a hook adapted for supporting meat, a hammock, hat, &c., the same being formed of a back plate and a hook, the latter being adapted to interlock with the former in a manner as will be hereinafter fully set forth.

Figure 1 represents a perspective view of a hook embodying my invention. Fig. 2 represents a front view of the back plate thereof. Fig. 3 represents a perspective view of the 20 hook, taken from the rear, the parts being separated. Fig. 4 represents a central vertical section thereof.

Similar letters of reference indicate corresponding parts in the several figures.

25 Referring to the drawings, A designates a back plate, having therein a slot B, which may be said to be T-shaped. In the rear of said plate is a recess C, the wall of which, at the bottom thereof, has a depression forming a groove D, it being noticed that the slot B is in communication with the recess C and the latter is in communication with the groove D.

30 E designates a hook having at its back a T-shaped head F, the several parts described being formed of suitable metal or other material.

The operation is as follows: The parts being separated, the hook is presented to the 40 back plate A, as shown in Fig. 3. The head F, which is in horizontal position, is inserted into the upper limb of the slot B and the hook rotated a quarter-turn, the head F then moving in the recess C until it is in upright position. The hook is now lowered, and the 45 lower end of the head F enters and is seated

in the groove D, whereby the hook is prevented from rotation, and as the head stands at a right angle to the upper limb of the slot B and is in contact with the rear wall of the 50 plate A above and below said slot it is evident that the hook is reliably interlocked with said plate. In the downward movement of the hook the neck G of the head F enters the vertical limb B' of the slot B and engages with the walls thereof, thus providing additional security for the connection of the hook with the plate. 55

In order to remove the hook, it is raised so that the head is clear of the groove D, after 60 which a quarter-turn is imparted to the hook, so that the head F registers with the upper limb of the slot B, when, as is evident, by the outward movement of the hook, the head F moves through the slot B and is entirely clear 65 thereof.

It will be seen that, by the present construction, in addition to providing an inexpensive and easily-operating device, I dispense with keys, catches, &c., and am also 70 enabled to support the back of the hook directly against the front faces of the back plate, avoiding wrenching out of the hook, said plate being secured in position by screws or other means in any suitable manner. 75

Having thus described my invention, what I claim as new, and desire to secure by Letters Patent, is—

A hook having a T-shaped head on its shank extending in the direction of the length thereof, in combination with a plate having an opening in its face adapted to receive said head, and a recess in the rear thereof, in which said head can partially rotate, said recess having a groove in its lower end adapted to receive 85 one end of said head, substantially as described.

WILLIAM B. CHARLTON.
